UNITED STATES PATENT OFFICE

2,553,381

FOUNTAIN PAINTBRUSH

William Carl Renne, Kansas City, Mo.

Application June 18, 1945, Serial No. 600,188

4 Claims. (Cl. 15—128)

1

This invention relates to an improved fountain paint brush and more particularly to a brush having a controlled flow of paint according to the surface requirements to be painted.

This invention has for its principal object a brush having a flexible handle with a rocker valve mounted therein to remain normally closed and intermittently and automatically opened by means of the painter's hand through the flexible handle in the normal manual operation of brushing paint on the surface of an object.

Another object of the present invention is to provide a flexible apron to tightly grip around the bristles of a brush attached to the crosshead of a handle, and extend over a considerable portion of the length of the bristles in a flexible gripping manner to prevent the paint from flowing back on the brush and for painting in any position especially in a substantially vertical or overhead position.

Another object of the present invention is to provide external means for adjustment of the compression spring of the paint flow rocker valve whereby the quantity and paint flow may be properly regulated according to the viscosity of the paint fluid.

Another object of the present invention is to provide an improved flexible shell to provide a divided fountain handle with parts that can be removed for access to cleaning the interior thereof.

With these and other objects in view the improved invention further consists of combinations of parts illustrated in the accompanying drawing, described in the specification and more fully pointed out in the claims appended hereto or by amendment.

Figure 1 is a side view in elevation illustrating the improved fountain paint brush with certain parts broken away to illustrate internal construction.

Figure 2 is an end view in elevation of Figure 1.

The crosshead 3 has the upper end of the bristles 4 normally embedded therein in the usual and well known manner, the bristles being of usual length extend downward therefrom and have a flexible apron 5 tightly gripping around the bristles 4 for substantially half the length thereof, the upper end of the apron being tightly stretched around the cross head 3 is seated in the depression 6 of the crosshead and prevents the paint from flowing on the outside of the crosshead and bristles before it has reached the useful part of the bristles for spreading the paint.

The crosshead 3 has a pipe coupling 7 rigidly

2

secured in the upper portion thereof, the coupling 7 having a tube 8 extending downwardly therefrom and through the crosshead into the bristles 4. The tube 8 has the lower end 9 thereof closed and small orifices 10 for proper distribution of the paint.

The rigid stock handle 11 has a tube 12 embedded therein and extending downwardly therethrough to screw into the coupling 7, the lock nut 13 being on the tube 12 and tightened against the coupling 7 for the purpose of holding the crosshead in proper position on the handle. The upper end of the tube 12 is threaded to receive the pipe bushing 14, the bushing and upper end 15 of pipe forming a seat 15 for the rocker valve 16 that is normally held closed by a compression spring 17. The spring 17 is held in position and adjusted by a valve stem screw 18 threaded into the valve 16 at 19 and extending through the upper end 20 of the flexible shell handle 21, the upper end of the valve stem screw 18 having a head 22 adapted to be turned by the fingers of a painter. The flexible shell handle 21 engages the stock handle 11 at threads 26 to seal the chamber formed thereby and retain paint under pressure.

A valve guide sleeve 23 is threaded on one end thereof and screwed on pipe bushing 14, the sleeve is embedded in the stock handle, open on the upper end thereof, and has a tube 24 secured thereto for a hose connection, the hose 25 being connected to the tube 24 and supplying paint from a remote pressure vessel.

In the operation paint is supplied through a hose to the fountain paint brush from an outside source, preferably from a pressure vessel. The paint flows through the tube 24, sleeve 23 and into the flexible shell handle 21 where it remains under static pressure until the flexible handle is tilted slightly in any direction from the polar axis of the valve stem releasing the paint to flow through the tubes 8 and 12. A small quantity of paint will then flow through the small orifices 10 to the bristles 4 and be confined within the apron 5 until it substantially reaches the brushing end of the bristles.

The valve may be manually adjusted by turning the head 22 of the valve stem screw 18 to regulate the flow of paint. The handle containing tube 12 is easily attached or detached to the cross head and coupling 7 and when attached is locked in position by the lock nut 13. The purpose of removing the crosshead from the handle is to change paint colors, and preferably having a different brush for each color for single handle.

What I claim as new and desire to secure by Letters Patent is:

1. A fountain paint brush having bristles embedded in a head comprising; a flexible shell handle, a rigid elongated member, said rigid elongated member connecting said flexible shell handle rigidly to said paint brush head, a tube, said tube extending from the inside of said flexible shell handle through said rigid elongated member and head to said bristles, a valve, said valve seated on said tube opening toward said flexible shell handle, a valve stem, said valve stem connected to said valve and being connected to said flexible shell handle, a compression spring, one end of said compression spring compressing said valve against said tube and the opposite end of said compression spring pressing against said flexible shell handle, a supply tube, said supply tube leading to the inside of said flexible shell handle, and said valve being open when rocked on said tube by said valve stem through the side actuation of said flexible shell handle by the hand of a painter.

2. A fountain paint brush as in claim 1 including means for adjusting the valve opening space from the exterior of said flexible shell handle.

3. A fountain paint brush having bristles embedded in a head comprising; a flexible reservoir handle, a rigid elongated member, said rigid elongated member connecting said flexible reservoir handle rigidly to said paint brush head, a tube, said tube extending from the reservoir of said flexible handle through said rigid elongated

member and head to said bristles, a valve, said valve seated on said tube opening toward said flexible reservoir handle, a valve stem, said valve stem connected to said valve and passing through the reservoir and being connected to said flexible reservoir handle, a compression spring, said compression spring compressing said valve against said tube and pressing against said flexible reservoir handle, a supply tube, said supply tube leading to the reservoir of said flexible reservoir handle, and said valve opened when rocked on said tube by said valve stem through the side actuation of said flexible reservoir handle by the hand of a painter.

4. A fountain paint brush as in claim 3 including means for adjusting said valve opening on said tube.
